UNITED STATES PATENT OFFICE.

WILLIAM LUTHER HANE, OF OCALA, FLORIDA.

COMBINATION-TOOL HOLDER

1,086,569.

Specification of Letters Patent.

Patented Feb. 24, 1914.

Application filed July 2, 1913. Serial No. 777,662.

To all whom it may concern:

Be it known that I, WILLIAM L. HANE, a citizen of the United States, and a resident of Ocala, in the county of Marion and State of Florida, have invented a new and useful Improvement in Combination-Tool Holders, of which the following is a specification.

My invention is an improvement in combination tool holders, and has for its object 10 to provide a simple, inexpensive holder of the character specified, for use with lathe planers and shapers, and wherein the holder may perform a plurality of functions, thus resulting in economy in both time and labor.

15 In the drawings:—Figure 1 is a perspective view of the improved holder, Fig. 2 is a longitudinal section, and Fig. 3 is a section on the line 3—3 of Fig. 2.

The present embodiment of the invention 20 comprises a shank 1, having one of its ends reduced on opposite faces, to form two surfaces 2 and 3, on the opposite sides of the holder, which are parallel and inclined with respect to the adjacent faces of the shank. 25 The shank is provided with a transverse opening 4, at the reduced end, the axis of the opening being perpendicular to the surfaces 2 and 3, and as a consequence inclined with respect to the axis of the holder.

30 A tool post is arranged within the opening 4, the said post comprising a body portion 5, having a head 6, at one end and the post is arranged in the opening with the head 6, engaging the surface 3, at the reduced end. The post is provided with a transverse slot 7, intermediate its ends, and the opposite end of the post from the head has a longitudinally extending internally threaded opening 8, which extends into the 35 slot 7 at the axis of the post.

A set screw 9 is threaded into the opening 8, the said set screw having at one end a head 10, polygonal in cross section for engagement by a tool to turn the set screw, 45 and the opposite end of the set screw is plain, as indicated at 11. The tool 12 is arranged within the slot 7, before mentioned, and a block 13 is used in connection with the set screw for holding the tool in 50 adjusted position.

The slot 7 is of greater length than the thickness of the tool, and is so arranged with respect to the body of the post that when the head 6 engages the surface 3 of the shank, approximately half the length of the slot will be within the opening 4. That

end of the opening 4 at the surface 2 is counterbored or reamed as indicated at 14, the said counterbored or reamed portion being formed on the segments of a sphere, 60 whose center is within the axis of the post.

The block 13, before mentioned, has one face 15 plane, for engaging the tool and the opposite face 16 is curved longitudinally of the block, the curve corresponding to the 65 shape of the counterbored portion of the opening 4. The block is of such thickness, that when the convex face thereof engages the counterbored end of the opening 4, the plane face 15 thereof will be extended beyond the surface 2, as shown more clearly in Fig. 2.

The block is so constructed with respect to the slot 7, that when in the position above named, the convex surface of the block will 75 not engage the adjacent end of the slot 7. The block 13 is for reinforcing the tool, which would otherwise rest against the surface 2 at its ends, and with that portion engaged by the set screw, unsupported on 80 the opposite side from the set screw. The block thus provides counter pressure for the screw and reinforcement for the tool.

The holder is in fact a shank having at one end an opening whose axis is inclined 85 with respect to the axis of the shank, and the tool post is held in the opening, the said post having means for supporting a tool in such manner that the axis of the tool may take a variety of positions with respect to the axis 90 of the holder.

In using the tool holder, the tool 12 may be arranged in any desired position with respect to the shank. When the set screw 9 is loosened, the post may be rotated in the 95 opening of the shank, to turn the tool at any desired angle with respect to the shank, and when the set screw is tightened, the tool is clamped firmly in place and the post is also clamped in adjusted position with respect to the holder.

When it is desired to remove the tool it is only necessary to loosen the set screw 10. The tool may be then removed, and a new tool inserted. After the tool has been adjusted with respect to the shank, the tightening of the set screw will clamp both tool and post in adjusted position. The shank 1 may be placed in the tool holder of the lathe or other device with which it is used. 110

I claim:

1. A holder of the character specified,

comprising a shank having a transverse opening at one end whose axis is perpendicular to the faces of the reduced end, a tool post arranged within the opening and having at one end a head for engaging the adjacent face of the shank to hold the tool from movement in the opposite direction, said post having a transverse slot, and an internally threaded longitudinal opening leading into the slot at the opposite end from the head, the slot of the post extending into the opening of the shank when the head is in engagement with the opposite face of the shank, and the opposite end of the opening of the shank from the head being counterbored, a set screw threaded through the longitudinal opening of the shank, and a block having one face plane to engage the opposite face of the tool from the set screw and having the opposite face curved longitudinally of the block to engage the counterbored portion of the opening.

2: A holder of the character specified, comprising a shank having a transverse opening and a tool post for engaging the opening, said post having a head at one end for engaging the adjacent face of the shank to limit the movement of the post through the opening, the post having a transverse slot intermediate its ends and extending into the opening of the shank when the post is in place in the opening, said post having a longitudinal internally threaded opening extending from the opposite end from the head into the slot, a set screw engaging the open-

ing, said opening being adapted to receive a tool, and the said screw being adapted to engage one face thereof, and a block in the slot and of greater length than the diameter of the opening of the shank for engaging the opposite face of the tool from the set screw, said block having the face adjacent to the shank curved longitudinally, and the adjacent end of the shank opening being counterbored.

3. A holder of the character specified, comprising a shank having a transverse opening and a tool post for engaging the opening, said post having a head at one end for engaging the adjacent face of the shank to limit the movement of the post through the opening, the post having a transverse slot intermediate its ends and extending into the opening of the shank when the post is in place in the opening, said post having a longitudinal internally threaded opening extending from the opposite end from the head into the slot, a set screw engaging the opening, said opening being adapted to receive a tool, and the said screw being adapted to engage one face thereof, and a block in the slot and of greater length than the diameter of the opening of the shank for engaging the opposite face of the tool from the set screw.
